UNITED STATES PATENT OFFICE.

MARQUIS L. JOHNSON, OF MANKATO, MINNESOTA.

APPARATUS FOR THE SALVAGE OF VESSELS.

1,073,990.

Specification of Letters Patent.

Patented Sept. 23, 1913.

Application filed March 11, 1913. Serial No. 753,611.

To all whom it may concern:

Be it known that I, MARQUIS L. JOHNSON, a citizen of the United States, residing at Mankato, in the county of Blue Earth and 5 State of Minnesota, have invented a new and useful Apparatus for the Salvage of Vessels, of which the following is a specification.

This invention relates to apparatus for the salvage of vessels.

10 An object of the present invention is to provide means whereby a vessel may be easily and readily raised.

A further object of the present invention is to provide a buoy secured to a vessel 15 whereby the said buoy may float and remain upon the surface of the water should the vessel to which it is attached sink.

20 A further object of the present invention is to provide a post upon an upper portion of the vessel and securely attach the same to the various decks and hull thereof and to further provide means whereby a cable with a ring secured to one end thereof may be brought in contact with and adapted to engage 25 the said post whereby the vessel may be raised.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the drawings accompanying this specification and forming a part thereof, the preferable form of my invention is illustrated, in which—

40 Figure 1 is a view of the buoy as positioned upon an upper deck of a vessel. Fig. 2 is a vertical cross sectional view illustrating the securing post and the reel secured 45 therewith, to which reel the buoy is fastened. Fig. 3 is a view in perspective of the post as secured to the upper deck of a vessel and with a cable with a ring attached to the end thereof engaging the upper portion of said post.

45 Referring to the drawings in which similar reference numerals designate corresponding parts throughout the several views, 1 represents the top deck or portion of a ves-

sel and 2 represents a hermetically sealed 55 buoy positioned thereon. The said buoy is normally held in place and stationary upon the deck 1 by means of the beams 3 which are hingedly secured to the vessel deck and allow that the buoy may readily float upwardly therefrom should the vessel become submerged. It is to be noted in this connection that the particular shape or structure of the buoy does not constitute any part of the present invention, the buoy as shown 60 65 serving to represent a conventional type only.

Secured upon the uppermost deck 1 of the vessel is the post comprising a base 4, a restricted central portion 5 extending upwardly therefrom the upper portion of 70 which is provided with the outward and downwardly extending arms or projections 6. Secured to or formed integral with the base 4 of the post are the spaced arms or 75 members 7 which extend downwardly through the various decks with which the hull is provided and are securely attached to each and every one thereof and terminate at the bottom of the hull to which they are 80 rigidly secured. By this means it will be apparent that any upward pressure exerted upon the said post will be transmitted through and to the various decks and to the hull with the result that when a cable is 85 secured to the said post, by exerting an upward force thereon, the entire vessel may be raised, it being noted in this connection that a number of buoys and posts therefore may be secured to a vessel, the number depending 90 upon the strength of the post and the size of the vessel and also the practical stress which may be exerted upon the cable which 95 may be secured to the post.

The post is provided with an aperture 8 extending centrally therethrough as illustrated in Fig. 2 of the drawings and through which opening extends a guide cable 9, the upper extremity of the cable being secured to the buoy 2 as illustrated in Fig. 1 100 and the lower portion thereof is secured upon a drum or wheel 10 upon which a suitable length thereof is wound. The said reel or drum 10 may be rotatably supported upon an axle 11 which is secured to the arms 105 7. The cable 9 is of a size and weight so that a considerable length thereof may be supported by means of the buoy 2, the ac-

tion being that when the vessel sinks or submerges, the buoy 2 with the cable 9 secured thereto will remain upon the surface of the water and as the vessel sinks the cable 9 will be unwound from the reel 10 until the vessel has assumed a position upon the bottom. The buoy 2 will remain upon the surface of the water and serve as a signal to indicate the position of the sunken vessel 10 as well as a guide by which a ring with a cable secured thereto may be passed over the spreading arms 6 of the post so that the cable may be secured thereto and the entire vessel raised.

15 As illustrated in Fig. 3 of the drawings, when it is desired to raise a vessel, the buoy 2 is removed from the top portion of the guide cable and a ring 12 is passed thereover, the said ring 12 being of considerable 20 strength and to which is secured a steel cable or chain 13 of considerable strength and the said cable and ring secured thereto are then lowered in the water and will be guided by means of the cable 9 until the ring 25 passes over the post and down upon the body portion 5 thereof, it being understood in this connection that it may require some little patience and effort to cause the ring 12 to successfully negotiate the enlarged 30 portions 6 of the post but by holding the cable 9 taut and suitably jarring the cable 13, the ring 12 will pass over the enlarged portion of the post and having once assumed the position as illustrated in Fig. 3 it will 35 be impossible for the ring to become accidentally detached from the post and furthermore when a suitable upward force upon the cable 13 is exerted the entire vessel will be raised, it being noted in this 40 connection that the invention is particularly useful in those cases in which a vessel sinks in a great depth of water and it is impossible to send a diver down to fasten raising cables thereto. Also mention is made of the 45 fact that the name of the vessel and length of cable attached thereto may be stamped upon the buoy.

Having thus fully described the invention,

what I claim to be new and original with me is:—

1. In an apparatus of the class described the combination of a post secured to the top deck of a vessel and provided with downwardly extending radial arms and an aperture extending longitudinally therethrough, 55 spaced arms connected to the said post extending downwardly through the vessel hull and secured to the various decks; a drum rotatably secured between the said arms and constituting a reel, a guide cable wound 60 upon said drum and extending through the said post aperture, a buoy disposed upon the top deck of the said vessel and secured to the said guide cable, and a lifting cable provided with an annular ring secured thereto 65 adapted to slide upon the guide cable for the engagement of the said post arms.

2. In an apparatus of the class described the combination of a post secured to the top deck of a vessel and including a base, spaced arms formed integral with the said base and extending downwardly through and secured to the various decks of the vessel, outstanding downwardly projecting arms connected to the upper extremity of said post, said post provided with an aperture extending centrally therethrough, a drum rotatably secured to the said first mentioned arms and in alignment with the post aperture, a guide cable wound upon the said drum and a buoy 70 resting upon the top deck of the vessel and connected to the said guide cable, means for preventing the shifting of said buoy, and a lifting cable provided with an annular ring secured thereto, said annular ring encompassing the guide cable for the engagement of the former with the outwardly and downwardly projecting arms of the post.

In testimony that I claim the foregoing as my own, I have hereto affixed my signature 90 in the presence of two witnesses.

MARQUIS L. JOHNSON.
